UNITED STATES PATENT OFFICE.

CHARLES E. HEIL, OF CLEVELAND, OHIO.

DEVICE FOR APPLYING TOILET POWDER.

1,042,673.

Specification of Letters Patent.

Patented Oct. 29, 1912.

Application filed January 18, 1912. Serial No. 671,785.

To all whom it may concern:

Be it known that I, CHARLES E. HEIL, a citizen of the United States of America, residing at Cleveland, in the county of Cuyahoga and State of Ohio, have invented certain new and useful Improvements in Devices for Applying Toilet Powder; and I hereby declare the following to be a full, clear, and exact description of the invention, 10 such as will enable others skilled in the art to which it pertains to make and use the same.

This invention relates to improvements in devices for applying toilet-powder and pertains more especially to a device of the character indicated in which a flexible sheet of material capable of carrying toilet-powder is wound on a roller when not in use and adapted to be unwound from said roller 20 for use.

The primary object of this invention is to provide a dust-guard instrumental in excluding dust from said sheet when the latter is wound on said roller, to inexpensively 25 and conveniently attach said sheet to the roller, to render said roller suitable for use as a receptacle for a case employed in holding toilet-powder, and to render the device simple and durable in construction and convenient.

With this object in view, and to the end of attaining other advantages hereinafter appearing, this invention consists in certain features of construction, and combinations 35 and arrangement of parts, hereinafter described, pointed out in the claim and illustrated in the accompanying drawings.

In said drawings, Figure 1 is a side view of my improved device for applying toilet-powder. Portions are broken away in this figure to more clearly show the construction. Fig. 2 is a central longitudinal section on line 2--2, Fig. 1, looking in the direction indicated by the arrow. Fig. 3 is a transverse section on line 3--3, Fig. 1, looking in the direction indicated by the arrow. Fig. 4 is a transverse section corresponding with Fig. 3, except that in Fig. 4 the dust-guard is shown in a different position than in 50 Fig. 3.

Referring to said drawings, A indicates a roller which is provided at one end with a head, a, employed in rotating the roller. Said roller has bearing at its other end in a 55 relatively stationary head B (see Fig. 2) and is provided at the outer end of said

head and externally with a laterally and outwardly projecting annular flange 5 overlapping the outer end face of said head and instrumental in preventing displacement of the roller endwise inwardly from said head. The head B forms a member of a case which 60 comprises a tubular shell C which is circular in cross-section. The shell C surrounds and is concentric relative to the roller. The shell C is large enough diametrically or 65 transversely to form an annular chamber 6 around the roller. The shell C embraces and is attached to the head B and extends from said head to the head a and engages an annular recess 7 with which said last-mentioned head (see Fig. 2) is provided at its 70 inner end face, which recess is concentric relative to the roller. The shell C affords bearing therefore to the head a. The shell 75 C has a slot 8 which extends longitudinally of said shell.

A flexible sheet D of material, such, for instance, as chamois, capable of carrying toilet-powder, is wound on the roller and 80 removably attached to the roller. Preferably the sheet D is provided at its inner end (see Figs. 1 and 2) with two tongues or members 10 projecting from opposite side edges respectively of said sheet. Eyes 12 85 are stitched or otherwise secured to said projecting members 10 and engage hooks or projecting members 13 formed on and preferably struck outwardly from the roller. The sheet D is not as wide as the slot 8 is 90 long, and said slot is wide enough to permit said sheet to pass therethrough. The sheet D is provided at its outer end and centrally between its side edges with a thumb-and-finger piece d which is thick enough or 95 large enough in dimensions to prevent it passing through the slot 8 and therefore projects outwardly from said slot upon winding said sheet on the roller.

A tubular dust-guard which consists preferably of a metal tube E which is circular in cross-section, is rotatably mounted and has bearing therefore on the shell C. The tube E is concentric relative to the roller. The tube E extends endwise of the shell C 105 from a point in proximity to the head B to a point in close proximity to the head a of the roller. The tube E has a slot 14 extending longitudinally of said tube and corresponding in length to the length of the slot 8. The tube E in the position shown in Figs. 1, 2, and 3 has its slot 14 in registry

with the slot 8. The slot 14 is preferably wide enough to permit the thumb-and-finger piece *d* to pass therethrough. It will be observed therefore that the slot 14 has the dimensions required to permit the passage therethrough of the sheet *D* and its thumb-and-finger piece *d*. The tube *E* is provided centrally between the side edges of the sheet *D* with an outward bulge *e* which extends 5 circumferentially of said tube and forms a recess 15 internally of the bulging portion *e* of said tube, which recess extends therefore circumferentially of the shell *C* and is arranged to receive the thumb-and-finger piece 10 *d* of the sheet *D*. Said bulging portion of the tube *E* therefore accommodates the location of said thumb-and-finger piece during the shifting of said tube circumferentially of the shell *C* to bring the slot 14 into or out 15 of registry with the slot 8. For instance, Fig. 4 shows the tube or dust-guard *E* rotated into a position in which its slot 14 is out of registry with the slot 8 and said dust-guard covers the last-mentioned slot, 20 but of course said dust-guard has to be shifted circumferentially of the shell *C* into a position in which the slot 14 registers with the slot 8, as shown in Figs. 1, 2, and 3, preparatory to unwinding the sheet *D* from the 25 roller. The slot 14 is preferably enlarged in width, as at 16, as shown in Figs. 3 and 4, at the outwardly bulging portion *e* of the dust-guard, to afford convenient access to the thumb-and-finger piece *d* of the sheet *D* 30 35 when said dust-guard is in the position shown in Figs. 1, 2, and 3. The dust-guard *E* is loosely interposed between the head *a* of the roller and a cap *H* which is removably mounted on the shell *C* where said shell 40 45 braces the head *B*. The roller is tubular from the flanged end of the roller a suitable distance toward the other end of the roller to form a receptacle for a case *G* which is inserted endwise into the roller at the flanged end of the roller and is removable from the roller. The case *G* is provided with a suitably applied cap *g* and adapted to hold a supply of toilet-powder.

The cap H conceals the adjacent end of the roller and the adjacent end of the case G, and said cap is large enough in dimensions to permit the reception within the outer end-portion of the cap,—that is, between the case G and the outer end of the cap,—of a cup-shaped receptacle K adapted

to hold a supply of toilet-powder, which receptacle is shown contained within the outer end-portion of said cap and has its bottom k perforated, as at 17. The receptacle K is provided centrally with an endwise shiftable pin L which extends through the bottom k and is provided with two heads 18 and 20 formed on opposite ends respectively of the pin and externally and internally respectively of said receptacle. The head 18 serves as a handle instrumental in withdrawing the receptacle K from the cap H upon the removal of said cap from the shell C, and the head 20 prevents disconnection of the pin L from said receptacle in withdrawing said receptacle through the medium of said pin from within said cap upon removal of the cap. 60 65 70

What I claim is:—

In a device for applying toilet-powder, 75
the combination, with a roller, a case comprising a shell which extends longitudinally of the roller and is concentric relative to the roller, which shell is enough larger transversely than the roller to form a chamber 80 around the roller and has a slot extending longitudinally of the shell, and a flexible sheet of material capable of carrying toilet-powder and connected to the roller and adapted to be wound on and unwound from 85 the roller through said slot, which sheet is provided at its outer end with a thumb-and-finger piece arranged centrally between the side edges of the sheet and projecting outwardly from said slot when the sheet has 90 been wound on the roller, of a dust-guard mounted on and extending longitudinally of the aforesaid shell, which dust-guard has a slot extending longitudinally of the 95 dust-guard and is shiftable circumferentially of said shell to bring its slot into or out of registry with the aforesaid slot in said shell, said dust-guard having an outwardly bulging portion which forms a recess which extends circumferentially of said 100 shell and is arranged to receive the aforesaid thumb-and-finger piece.

In testimony whereof, I sign the foregoing specification, in the presence of two witnesses.

CHARLES E. HEIL.
